(57) **CLAIM**

The ornamental design for a chassis assembly for broadband network head-end modules, as shown and described.

DESCRIPTION

FIG. 1 is a front elevational view of a chassis assembly for broadband network head-end modules showing our new design.

FIG. 2 is a top plan view thereof;

FIG. 3 is a right side elevational view thereof, the left side elevational view is a mirror image of FIG. 3; and,

FIG. 4 is a perspective view thereof, showing in dashed lines a representative broadband network head-end combining module mounted to the chassis assembly for broadband network head-end modules.

The dashed lines are for illustration and environment only and do not form a part of the claimed design.
